BLADE MOUNTING FOR GRADING MACHINES

Albert R. Henry, Salina, Kans., assignor to Henry Manufacturing Company, Inc., Topeka, Kans., a corporation of Kansas

Application November 27, 1944, Serial No. 565,260

5 Claims. (Cl. 37—144)

1

This invention relates to improvements in blade mounting for grading machines and has particular reference to scraper blade mountings whereby the angle of the blade to the ground level may be varied.

The blade mounting shown in the drawings is used in conjunction with a machine shown in my pending application Serial No. 491,717, dated June 21, 1943, and which has since issued as Patent No. 2,379,522.

The principal object of the invention is the provision of scraper blade mounting having adjustable means whereby the angle of inclination of the blade to the earth surface being worked may be varied.

Another object is the provision of blade mounting having a vertically adjustable depth gauge whereby the depth of cut of the blade may be varied.

Other objects are simplicity and rigidity of construction, ease of adjustment, and adaptability for use with most of the various types of grading machines wherein push arms are used to propel a grader blade.

Having these objects in view as well as other objects which will appear during the course of this specification, reference will now be had to the drawings wherein:

Figure 1 is a plan view of a grader blade and mounting, partly in section and embodying this invention.

Fig. 2 is a vertical sectional view taken on line II—II of Fig. 1.

Fig. 3 is a side elevation of the blade mounting means shown in Fig. 1.

Fig. 4 is an enlarged cross sectional view taken on line IV—IV of Fig. 2.

Fig. 5 is a sectional view taken on line V—V of Fig. 4.

Fig. 6 is an elevational view of the adjusting member.

Fig. 7 is a sectional view taken on line VII—VII of Fig. 4.

Throughout the several views like reference characters refer to similar parts and the numeral 10 designates a fragmentary sectional view of a loading device frame, adapted to be attached to a tractor as clearly shown in my pending application referred to above.

This frame carries upwardly extending track

members 12, which serve to receive the rollers 14 carried by the side arms 16 of boom 18 which is adapted to be raised and lowered by cables 20 as described and shown in the pending application. 5 Boom 18 has a cross bar 22 and forwardly extending arms 24. The side arms of the boom 18 serve as push members when they are in the lowered position as shown.

While this particular type of loading device has 10 been shown in conjunction with the invention, however, it is quite apparent that it might be used with other scraping machines or bulldozers having push arms.

The feature of novelty of the present invention 15 is the blade mounting means whereby the angled relation of the blade to the earth surface may be varied and whereby the depth of cut of the blade may be changed to suit the type of work being done; also the blade may be positioned above the earth surface when performing certain bulldozing operations.

The blade 26, having a removable bit 28 and a curved upper portion 30, is suitably reinforced by angle bar 34, top angle iron 32, and vertically extended edge flanges 36, is pivotally mounted adjacent its opposite ends to boom arms 24 by pins 38 which pass through holes 40 formed through parallel plates 42 and 44 integral with the blade and which straddles the end of the respective arms 24 as clearly shown in Fig. 5, so that pin 38 will pass through a sleeve 46 mounted in said arm. Another plate 48 parallel with and spaced apart from plate 44 both of which extend substantially to the top of the blade are reinforcing means for the blade and also serve to receive one end of an adjusting member 50 therebetween. This adjusting member comprises two side plates 52, each having a notch 54 to fit over cross bar 22 as clearly shown in Fig. 4. Plates 52 are positioned in parallel relation and are joined together by a pair of parallel plates 54 and 56 to form with the side plates 52 a substantially vertically disposed rectangular tube 58. The forward end of member 50 positioned between plates 44 and 48 is transversely perforated at 61 to receive the extended end of pin 38 which passes through a hole formed through plate 48. When thus mounted the adjustment member 50 is securely held relative to the boom to serve as an anchoring means whereby the blade 26 may be adjusted

at various predetermined angles to the ground surface. A series of spaced apart holes 60 concentric with pin 38 is formed through side plates 52 above notch 54 so that a pin 64 extended through aligned holes (see Fig. 4) will serve to support the blade in a fixed angle relative to the ground. Plates 66 extended between plates 52 serve as reinforcements and as bearing members to rest against the top and bottom side of cross bar 22.

Slidably mounted in tubular member 58 is a tubular member 68 of rectangular cross section. A tiltable shoe 70 comprising a base portion 72, a forward inclined end plate 74, a rearwardly inclined plate 76, and parallel spaced apart longitudinal ribs 78 between which the lower end of member 68 is adapted to fit serves as a foot to rest on the earth to the rear of the scraper blade. The lower end of member 68 is perforated at 80 to receive the bolt 82 which passes through holes 84 formed through ribs 78 to support the shoe 70 for oscillating movement relative thereto. The lower end of member 68 is angled forwardly and rearwardly from its central portion to permit limited free movement of the shoe, and to also serve as a stop at both sides of the pivotal point to contact base 72.

A series of holes 74 formed through the side walls of member 68 are disposed in alignment with hole 76 formed through side walls 52 of member 50 adjacent its lower edge and may be adjusted relative thereto so that pin 78 may be positioned therethrough to secure members 50 and 68 in fixed relative relation.

In the operation of this blade mounting means, the only requirement for changing the angle of blade 26 relative to the earth surface is to simply remove pin 64, and adjust the blade about its pivot 38 until the proper hole 60 is in register with hole 62 and then inserting pin 64 to secure the blade and member 50 against relative movement. When it is desired to change the depth of cut or to position the bit of the blade above the earth surface, the operator simply removes pin 78, raises or lowers member 68 in the tubular passageway 58 until the proper holes in series 74 registers with hole 76 and inserts pin 78 to maintain these parts in fixed relation so that when the shoe 70 is positioned on the ground the bit 28 will be positioned in the desired position relative to the ground's surface.

It is quite apparent that this type of mounting may be used on substantially any blade type scraper or bulldozer having push arms joined together with a cross bar. The type of tractor or lift is not material to the proper operation of the blade mounting.

What I claim as new and desire to cover by Letters Patent is:

1. A scraper blade mounting comprising a pair of pusher arms joined together by a cross bar of rectangular cross section, a blade pivotally mounted on the front end of said pusher arms, a plate substantially the full vertical width of the blade extending rearwardly from said blade and having a series of holes concentric with the pivotal axis of said blade, an adjusting member provided at its rear edge with an open rectangular slot adapted to snugly engage said cross bar and secured at its front end to a pin in axial alignment with the pivot of said blade whereby it is carried in fixed relation to said arms and having a hole adapted to selectively register with the holes of said series, and means adapted to be extended through the registered holes to interconnect said

plates with said adjusting member whereby to secure said blade at a predetermined angle relative to said push arms.

2. A scraper blade mounting comprising a pair of pusher arms joined together by a cross bar, a blade pivotally mounted on the front end of said pusher arms, a plate extending rearwardly from said blade adjacent each of said pusher arms each having a series of holes concentric with the pivotal axis of said blade, an adjusting member secured at its front end to the pivot of said blade and notched rearwardly at its rear edge to fit on said cross bar whereby it is carried in fixed relation to said arms and adjacent each of said plates, each having a hole adapted to selectively register with the holes of the adjacent series, means adapted to be extended through the registered holes to interconnect said plates with said adjusting members whereby to secure said blade at a predetermined angle relative to said push arm, a member mounted for vertical adjustment in said adjusting member, and a shoe pivotally mounted on the lower end of said adjustable member for limited tilting movement relative thereto.

3. A scraper blade mounting comprising a pair of pusher arms joined together adjacent their outer ends by a cross bar, a blade pivotally mounted on the front end of said pusher arms, a plate extending rearwardly from said blade and having a series of holes concentric with the pivotal axis of said blade, an adjusting member fixed at its front end to the pivot of said blade and notched at its rear edge to fit over said cross bar whereby it is carried in fixed relation to said arms and having a hole adapted to selectively register with the holes of said series and formed to present a substantially vertically disposed tubular portion, a pin adapted to engage in said registered holes whereby the blade is secured at a fixed, selected angle relative to said pusher arms, a member adjustably mounted in the tubular portion of said adjusting member and extending therebelow, a shoe tiltably mounted adjacent the lower end of said adjustable member.

4. A scraper blade mounting comprising a pair of pusher arms having a connecting cross bar, a scraper blade pivotally mounted on the front end of said pusher arms, a plate extending rearwardly from said blade and having a series of holes concentric with the pivotal axis of said blade, an adjusting member notched at its rear edge to fit over said cross bar and secured at its forward position to the pivotal mounting of said blade, whereby it is secured in fixed relation to said arms and having a hole adapted to selectively register with the holes of said series, whereby the plate and adjusting member may be relatively adjusted, a securing pin to pass through said registering holes, and a foot member adjustably carried by said adjusting member whereby the vertical position of the blade relative to the earth's surface being worked is varied.

5. A scraper blade mounting comprising a boom including a pair of push arms interconnected by a cross bar, a scraper blade disposed transversely of said tractor and pivotally connected to the front end of said boom by pins, plates rigidly attached to and extending rearwardly from said blade, each plate having a like series of holes concentric with the pivotal axis of said blade, adjusting members notched at their rear ends to engage said cross bar and perforated at their front ends to respectively receive the pivot pins of said blade and having holes adapted to be

moved to respectively register with the various holes of the series of holes in said plates whereby they are adjustably secured together by pins, said members being provided adjacent their central portions with a vertically disposed rectangular tube, a rectangular tubular member disposed for vertical adjustment in the tube of each of said adjusting members, and a tiltable shoe carried at the lower end of each of said tubular member for engagement with the earth's surface.
